TELEPHONE DIAL ADVERTISING DEVICE

Robert A. Bennett, Shelton, Conn., assignor to Peter D. Chapdelaine, Newtown, Conn.

Filed June 24, 1969, Ser. No. 17,856

Term of patent 14 years

Int. Cl. D14—03

U.S. Cl. D26—14

FIG. 1

FIG. 2

FIG. 3

FIG. 4

FIG. 7

FIG. 6

FIG. 5

FIG. 1 is a perspective view of a telephone dial advertising device according to my invention;

FIG. 2 is a bottom plan view thereof;

FIG. 3 is a top plan view thereof;

FIG. 4 is a left side view thereof;

FIG. 5 is a right side view thereof;

FIG. 6 is a front view thereof;

FIG. 7 is a top plan view of a modified telephone advertising device according to my invention; and

FIG. 8 is a partial cross sectional view taken along the line 8—8 of FIG. 7.

I claim:

The ornamental design for telephone dial advertising device, as shown and described.
